(57) **CLAIM**

The ornamental design for a napkin and coaster holder, as shown and described.

DESCRIPTION

FIG. 1 is a perspective view of a napkin and coaster holder showing our new design;

FIG. 2 is a top plan view thereof, shown at a reduced scale;

FIG. 3 is a front elevation view thereof;

FIG. 4 is a side elevation view thereof;

FIG. 5 is a bottom plan view thereof; and,

FIG. 6 is a perspective view of the napkin and coaster holder of FIG. 1 shown holding unclaimed coasters.

The dotted-line showing in the drawings illustrates environmental matter and forms no part of the claimed design.
